COMBINED STRAINER AND CONTAINER COVER

Earl S. Tupper, Smithfield, R.I., assignor to Tupper Corporation, North Smithfield, R.I., a corporation of Delaware

Application April 17, 1956, Serial No. 41,113

Term of patent 14 years

(Cl. D44—15)

Figure 1 is a view in perspective of a combined strainer and container cover, embodying my new design and showing a container associated therewith in phantom.

I claim:

The ornamental design for a combined strainer and container cover, substantially as shown and described.
